REACTANCE COMPENSATION SYSTEM

George H. Brown, Princeton, N. J., assignor to
Radio Corporation of America, a corporation of
Delaware

Application March 30, 1945, Serial No. 585,671

3 Claims. (Cl. 178—44)

This invention relates to reactance compensation, and more particularly to improvements in the art of neutralizing the effects of reactances which are unavoidably present in radio frequency power transmission circuits. As is well known to those skilled in the art, the frequency band width through which a transmission circuit operates efficiently to transfer power is a function of the shunt reactances in the circuit.

The principal object of the present invention is to provide improved methods of and means for compensating the effects of reactance in radio frequency transmission circuits.

Another object is to provide improved methods of and means for obtaining broad-band operation of radio frequency transmission circuits.

A further object is to provide improved methods of and means for compensating the reactances of short-circuited quarter wave line sections such as are used in line balance convertor systems and the like.

The invention will be described with reference to the accompanying drawing, of which:

Figure 1 is a schematic circuit diagram of a radio frequency transmission circuit embodying the instant invention.

Figure 2 is a schematic diagram of a compensated line balance convertor in accordance with prior art practice.

Figure 3 is a schematic diagram of a compensated line balance convertor in accordance with the present invention, and

Figure 4 is a modified form of the device shown in Figure 3.

Referring to Figure 1, it is assumed that a load 1, of impedance R , is to be energized from a source 3, having an internal impedance R , through a transmission line 5 having a characteristic impedance Z_0 . The value of Z_0 is made equal to the impedance R of the load 1 and the source 3, so that in the absence of any further circuit elements, the load 1 and line 5 will be matched to the source 3 at all frequencies, providing efficient transfer of power independently of frequency.

Suppose that it is necessary to connect across the load 1 a transmission line section 7, short-circuited at its end away from the load 1. It is well known that short-circuited transmission lines exhibit characteristics similar to those of parallel resonant circuits. Thus at the frequency at which the line 7 is one quarter wavelength long, a very high impedance, resistive in character, is presented across the load 1. At lower frequencies, the line 7 acts like an inductance connected to the load 1, while at higher frequencies the line 7 presents a capacitive reactance across the load 1.

As long as the reactance of the line 7 is very much greater than the impedance R of the load 1, there is substantially no impedance mismatch caused by the presence of the line 7. However, at

all frequencies outside of a relatively narrow band, the reactance of the line 7 will be of the same order as the impedance R , or lower. At any of these frequencies, a major portion of the current from the source 3 will flow through the line 7, causing serious impedance mismatch and preventing efficient transfer of energy from the source 3 to the load 1.

In accordance with the present invention, a short-circuited half wavelength line section 9 is connected in series with the load 1 and the quarter wave line 7. By proportioning the conductors of the line 9 to provide a surge impedance Z_2 which is a predetermined function of the load impedance R and the impedance Z_1 of the line 7, the line 9 may be caused to introduce reactance variations which are equal and opposite to those of the line 7, through a substantial range of frequencies.

The reactance presented by the quarter wave line 7 across the load 1, at a frequency f , is:

$$(1) \quad jZ_1 \tan\left(\frac{\pi f}{2 f_0}\right)$$

where f_0 is the frequency at which the line 7 is exactly one quarter wavelength long. The impedance Z_a of the load 1 and the line 7 in parallel:

$$(2) \quad Z_a = \frac{jRZ_1 \tan\left(\frac{\pi f}{2 f_0}\right)}{R + jZ_1 \tan\left(\frac{\pi f}{2 f_0}\right)}$$

rationalizing,

$$(3) \quad Z_a = \frac{jRZ_1 \tan\left(\frac{\pi f}{2 f_0}\right) [R - jZ_1 \tan\left(\frac{\pi f}{2 f_0}\right)]}{R^2 + Z_1^2 \tan^2\left(\frac{\pi f}{2 f_0}\right)}$$

The reactive component X_a of Z_a is:

$$(4) \quad X_a = \frac{R^2 Z_1 \tan\left(\frac{\pi f}{2 f_0}\right)}{R^2 + Z_1^2 \tan^2\left(\frac{\pi f}{2 f_0}\right)}$$

The rate of change of the reactance X_a as a function of frequency is:

$$(5) \quad \frac{dx_a}{df} = \left\{ \left[R^2 + Z_1^2 \tan^2\left(\frac{\pi f}{2 f_0}\right) \right] R^2 Z_1 \cdot \frac{1}{\cos^2\left(\frac{\pi f}{2 f_0}\right)} \cdot \frac{\pi}{2 f_0} - \right.$$

$$R^2 Z_1 \tan\left(\frac{\pi f}{2 f_0}\right) \left[2Z_1^2 \cdot \frac{\tan\left(\frac{\pi f}{2 f_0}\right)}{\cos^2\left(\frac{\pi f}{2 f_0}\right)} \cdot \frac{\pi}{2 f_0} \right] \left. \right\} \cdot$$

$$\left[R^2 + Z_1^2 \tan^2\left(\frac{\pi f}{2 f_0}\right) \right]^2$$

When $f=f_0$:

$$(5) \quad \left(\frac{dX_a}{df} \right)_{f=f_0} = \frac{\left[R^2 Z_1^3 - 2R Z_1^3 \right] \frac{\pi}{2f_0}}{Z_1^4} = -\frac{R^2}{Z_1} \left(\frac{\pi}{2f_0} \right)$$

The negative sign indicates that X_a is negative (i. e. capacitive) at frequencies higher than f_0 , and positive (inductive) at frequencies lower than f_0 .

The reactance of the half wave line 9 is:

$$(6) \quad X_b = +jZ_2 \tan \left(\pi \frac{f}{f_0} \right)$$

and the rate of change of reactance with change in frequency is:

$$(7) \quad \frac{dX_b}{df} = \frac{Z_2}{\cos^2 \left(\frac{\pi f}{f_0} \right)} \left(\frac{\pi}{f_0} \right)$$

When $f=f_0$:

$$(8) \quad \left(\frac{dX_b}{df} \right)_{f=f_0} = Z_2 \left(\frac{\pi}{f_0} \right)$$

Since the derivative

$$\frac{dX_b}{df}$$

is positive at the frequency f_0 , the reactance X_b is positive at frequencies higher than f_0 and negative at frequencies lower than f_0 .

The total reactance presented to the line 5 by the load 1 and lines 7 and 9 is the sum of the reactances X_a and X_b . At the resonance frequency f_0 , both are zero. The total reactance can be made to remain at zero over an appreciable range of frequency by making the rates of change of the two component reactances equal and opposite at f_0 :

$$(9) \quad \left(\frac{dX_a}{df} \right)_{f=f_0} = - \left(\frac{dX_b}{df} \right)_{f=f_0}$$

Substituting Equations 5 and 8,

$$(10) \quad \frac{R^2}{Z_1} \left(\frac{\pi}{2f_0} \right) = Z_2 \left(\frac{\pi}{f_0} \right)$$

and

$$(11) \quad Z_2 = \frac{R^2}{2Z_1}$$

From Equation 11, it is evident that the characteristic impedance Z_2 of the half wave line 9 may be determined from the load impedance R and the characteristic impedance Z_1 of the shunt quarter wave line 7 to provide substantial cancellation of the reactance in the neighborhood of the resonant frequency f_0 .

The described method of reactance compensation may be applied to the design of compensated line balance convertors, such as are used for transferring radio frequency power between balanced and unbalanced circuits or lines.

Referring to Figure 2, one well-known type of line balance convertor includes a cylindrical conductive sleeve 11 surrounding a quarter wavelength section 13 at the end of a coaxial transmission line 15. The line 15 comprises the unsymmetrical or unbalanced circuit of the convertor. The sleeve 11 is connected to the outer conductor of the line section 13 by a conductive disc 17. A pair of transmission lines 19 and 21 are connected to the inner and outer conductors respectively of the line section 13. The lines 19 and 21 comprise the balanced circuits of the convertor. The sleeve 11 is slightly more than one half wavelength long, and is closed at its upper end by a disc 23. A quarter wavelength rod 25 extends coaxially within the sleeve 11

from the disc 23 to the point of connection of the inner conductors of the lines 15 and 19.

A pair of quarter wave stub lines 27 and 29 are connected to the lines 19 and 21 respectively at points one quarter wavelength from the connections to the unbalanced line 15. The stubs 27 and 29 are similar to the upper portion of the convertor structure formed by the sleeve 11 and the rod 25.

In the structure of Figure 2, the outer conductor of the line section 13 cooperates with the lower portion of the sleeve 11 to act as a quarter wavelength short-circuited line, connected across the end of the balanced line 21. The rod 25 and the upper portion of the sleeve 11 act as a similar quarter wave line across the balanced line 19, so that the reactances across the lines 19 and 21 vary in the same way with variation in frequency, and the lines remain balanced.

As mentioned above, the reactances of the quarter wave lines will decrease to such an extent as to introduce serious impedance mismatch when the frequency of operation is materially different from the resonant frequency of the lines. This is counteracted to some extent by the quarter wave stubs 27 and 29, which vary in reactance in the same manner as the quarter wave lines 11, 25, and 11, 13. The reactance of the stub 27 is inverted by the final quarter wave section of the balanced line 19, providing an equal and opposite reactance at the point of connection to the line 13. This reactance cancels that of the rod 25 and sleeve 11. The stub 29 acts in the same manner to cancel the reactance presented by the outer conductor of the line section 13 and the sleeve 11. A compensated convertor of the type shown in Figure 2 will operate efficiently over a fairly wide frequency band, but has the disadvantage of structural complexity.

Referring to Figure 3, a line balance convertor embodying the reactance compensation of the present invention includes a sleeve 31, one half wavelength long at the mean operating frequency, surrounding the final half wavelength section 14 of the unbalanced line 15, and connected to the outer conductor thereof by a disc 18. A larger sleeve 111, similar to the sleeve 11 of Figure 2, surrounds the final quarter wavelength portion 32 of the sleeve 31, and a conductor 33, one quarter wavelength long and of the same diameter as the sleeve 31. The conductor 33 is connected to the sleeve 111 at its end by a disc 123.

The inner conductor of the unbalanced line 15 is connected to the conductor 33. The balanced lines 19 and 21 are connected to the adjacent ends of the conductor 33 and the sleeve 31.

The quarter wave lines formed by the sleeve 111 with the conductor 33 and the sleeve 31 are shunted across the balanced lines 19 and 21 respectively, and are in series with each other between the adjacent ends of the conductors 31 and 33. The unbalanced line is connected to these points through the half wave short-circuited line section 14, 31. It is evident that the arrangement is equivalent to that shown in Figure 1, except that two loads (the balanced lines 19 and 21) are connected in series with each other, and each is shunted by a quarter wave line. The reactances are compensated as described in connection with Figure 1, and the proper value for the characteristic impedance Z_2 of the half wave line section is still indicated by Equation 11 above, since both numerator and

denominator are doubled. It should be noted, however, that the characteristic impedance of the line 15 must be twice that of the lines 19 and 21 to provide proper matching. This is also true of the system of Figure 2.

Under certain conditions, it will be found that the impedance Z_2 must be so high that it is mechanically awkward to construct the device of Figure 3 with the proper ratio of diameters of the elements 111 and 31 to each other and still have the diameter of the sleeve 31 in the proper ratio to that of the outer conductor of the line section 14. In this event, the structure of Figure 4 is preferable. The final half wave portion 14 is surrounded, as in Figure 3, by a half wave sleeve 131, and the final quarter wave portion of the sleeve 131 extends into an outer sleeve 211, similar to the sleeve 111 of Figure 3. The conductor 33 of Figure 3 is replaced by a half wave sleeve 133 with a coaxial inner conductor 134 connected thereto at its outer end. The inner conductor of the unbalanced line 15 is connected to the inner conductor 134, which is of the same diameter as the outer conductor of the line 15.

The system of Figure 4 is equivalent to that of Figure 5, except that the half wave line is in two sections, connected in series with each other. With this arrangement the characteristic impedance Z_2' of the lines 14, 131 and 134, 133 is one half the impedance Z_2 required in the system of Figure 3. The reactances are compensated in the same manner as in the systems of Figures 1 and 3.

Although the invention has been described with reference to short-circuited line sections of lengths one quarter and one half wavelength respectively, the principle applies to lines which are certain multiples of the described lengths. Any of the sections described as one quarter wavelength long may be replaced by sections m quarter wavelengths long, where m is any odd integer, and the one half wavelength sections may be replaced by sections n half wavelengths long, where n is any integer. The impedance Z_2'' of the compensating (half wavelength) sections is then determined by the relation:

$$(12) \quad Z_2 = \frac{R^2 m}{2 Z_{1n}}$$

The invention has been described as an improved method of shunt reactance compensation, in which a half wavelength short-circuited line is connected in series with the element whose reactance is to be neutralized. By proper adjustment of the impedance of the half wavelength line, compensation is effected throughout a band of frequencies. Typical applications of the invention to line balance convertor systems have been described. It is to be understood, however, that the invention may be used in other similar situations where undesirable reactance is present.

I claim as my invention:

1. A line balance convertor including an unbalanced-to-ground circuit comprising a coaxial transmission line, a tubular conductor substantially one half wavelength long surrounding the final half wavelength portion of said line and connected to the outer conductor of said line at a point one half wavelength from the end thereof, a second tubular conductor one end of which surrounds the final quarter wavelength portion of said first-mentioned tubular conductor and is connected thereto at a point substantially midway of the length thereof a cylindrical quarter wavelength conductor which is surrounded by the

other end of said second tubular conductor and is connected at one of its ends to the end thereof and which has a diameter equal to the outside diameter of the first-mentioned tubular conductor, said coaxial line, said cylindrical conductor, and said first and second tubular conductors being concentric about a common axis, the other end of said cylindrical conductor being adjacent to and facing the end of said final portion of said first-mentioned tubular conductor, and a balanced-to-ground circuit comprising one conductor connected to the end of the inner conductor of said coaxial line of said adjacent end of the cylindrical conductor and another conductor connected to the adjacent end of said first-mentioned tubular conductor.

2. A radio frequency network for transferring energy between two terminations each of impedance R over an in-series circuit of an unbalanced-to-ground transmission line and a balanced-to-ground transmission line comprising an element in shunt to said circuit at the point of connection of the lines, the element being parallel resonant at a wavelength λ and exhibiting parallel resonant characteristics similar to those of a short circuited line of length substantially

$$\frac{m}{\lambda}$$

4

30 where m is any odd integer and the line has a surge impedance Z_1 , a reactance compensating device for said element comprising a transmission line, of length substantially

$$\frac{n}{\lambda}$$

35 where n is any integer and of surge impedance Z_2 , short circuited at one of its ends and connected at the other in series with one of the conductors of the balanced-to-ground line near its point of connection to the unbalanced-to-ground line, the surge impedance Z_2 of said line being such as substantially to satisfy the relation

$$45 \quad Z_2 = \frac{R^2 m}{2 Z_{1n}}$$

and a second reactance compensating device to compensate any residual reactance effects of the first compensating device, the second reactance compensating device comprising a transmission line of equal length and surge impedance to the first compensating device and being short circuited at one of its ends and connected at its other end in series with the other conductor of the balanced-to-ground line near its connection to the unbalanced-to-ground line.

3. A line balance convertor including an unbalanced-to-ground circuit comprising a coaxial transmission line, a tubular conductor substantially one half wavelength long surrounding the final half wavelength portion of said line and connected to its outer conductor at a point one half wavelength from the end thereof, a second tubular conductor substantially one half wavelength long one end of which surrounds the final quarter wavelength portions of said first-mentioned tubular conductor and the coaxial line within it and is connected to the former at a point substantially midway along its length, a second coaxial line which is one half wavelength long and short circuited at one end, has an inner conductor whose outside diameter is equal to that of the outer conductor to said first-mentioned line, and has an outer conductor whose side and outside diameters are equal to those of

said first-mentioned tubular conductor, a quarter wavelength portion of the open end of said second coaxial line being surrounded by the other end of said second tubular conductor and having the midpoint of its outer conductor connected thereto, all of said first and second coaxial line and said first and second tubular conductors being concentric about a common axis, the open end of said second coaxial line being adjacent to and facing the end of said final portion of said first tubular conductor, and a balanced-to-ground circuit comprising one conductor connected to one end of the inner conductor of said first-mentioned coaxial line over a connection including in series the conductors of the second coaxial line and another conductor connected to the adjacent end of said first-mentioned and tubular conductor.
